(57) CLAIM

The ornamental design for a child pajama, as shown and described.

DESCRIPTION

FIG. 1 is a front perspective view of a child pajama.

FIG. 2 is a rear perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a left-side elevation view thereof; and,

FIG. 8 is a right-side elevation view thereof.

The evenly dashed broken lines along the surfaces of the child pajama depict claimed stitching. The dash-dot-dash broken lines depict boundary lines and form no part of the claimed design.

1 Claim, 8 Drawing Sheets
